UNITED STATES PATENT OFFICE

FRED A. DAY, OF COLUMBUS, OHIO

HEEL BREASTING MACHINE

Application filed August 15, 1928. Serial No. 299,839.

REISSUED

This invention relates to improvements in heel breeding machines, and has for its primary object the provision of a simple yet efficient machine adapted for the purpose of 5 curve breeding wooden heel blanks. Heels of the type employed particularly in connection with women's shoes and particularly that style known as Cuban type of heel includes a breast surface which is concave transversely 10 of the heel. Vertically these breasts are convexly curved from the tread to the heel seat. By providing the breast surface of the heel blank with this compound curvature the complete blank heel when finished produces 15 what is known as a straight line effect at the planes of the joinder between the breast surface of the heel and the curved or turned sides thereof.

Heretofore it has been customary to shape 20 the breast surface of a heel blank as above described by arranging the heel blanks on a turnable support so that during the operation of said support the breast surfaces of the heel blanks are presented to the cutting 25 edge of a barrel-saw or crown type of cutter, so that in swinging the support in order to move the heel blank past the cutter there is produced in the breast surfaces of the heel blank the compound curvature set forth, 30 namely the concave curve horizontally and the convex vertically.

The present invention is directed to an improved machine by means of which this breeding operation may be more expeditiously and efficiently carried out, and wherein in the shape of the cutter produces of itself the compound curvature referred to, the holding or supporting means for the heel blanks being entirely independent of the 40 curvature produced on the breast surface of the blank.

The object of the invention resides in a heel breeding machine wherein is provided what is known as a "form" cutter which is 45 shaped to produce both the convex and concave curvature in the breast surface of a heel blank wherein supporting means are provided for moving the heel blank to the cutting face of the cutter by substantially 50 a reciprocating motion in lieu of a rotary

or turning motion and wherein the supporting means permit of the movement of the blank up to the cutter and away from the cutter but not past the same.

With these and other objects in view, which will appear as the description proceeds, this invention consists in the novel features of construction—convenience and arrangements of parts, hereinafter fully described and pointed out in the appended claims. 55

In the accompanying drawings:

Figure 1 is a view in side elevation of the heel breeding machine comprising the present invention,

Figure 2 is a top plan view of said machine, 65

Figure 3 is an end elevation thereof,

Figure 4 is a vertical longitudinal view taken through the machine on the plane indicated by the line 4—4 of Figure 2, 70

Figure 5 is a similar view disclosing the heel blank in a clamped position and presented to the action of the formed cutter,

Figure 6 is a vertical sectional view on the plane indicated on the line 6—6 of Figure 5, 75

Figure 7 is a horizontal sectional view on the line 7—7 of Figure 5,

Figure 8 is a detailed perspective view of the movable clamping jaw, 80

Figure 9 is a view in side elevation of the pivoted blank gauge showing the latter in its active position,

Figure 10 is a similar view showing the gauge in its inactive position, 85

Figure 11 is a perspective view of a heel blank formed in accordance with the present invention,

Figure 12 is a side elevation thereof,

Figure 13 is a vertical longitudinal sectional view through the heel blank, 90

Figure 14 is a horizontal sectional view through said blank.

Referring more particularly to the drawings the numeral 1 designates the frame of the improved heel breeding machine. At one end of the frame there is mounted a vertically disposed motor 2, the shaft of which drives a belt wheel 3. Around this wheel there passes an endless belt 4, which is also 95

passed over a wheel 5 provided upon a vertically disposed cutter shaft 6. This shaft is journaled in connection with bearings 7-7, mounted upon an upright standard 8, which forms a part of the frame 1.

6 The upper end of the shaft 6 carries a removable cutter 9. This cutter as shown, consists of a metal body of tool steel, formed to comprise a plurality of spiral curved cutting blades, the edges 10 of which are so arranged that the diameter of the lower part of the cutter exceeds, slightly, the upper part of the cutter, so that when the cutter is viewed in side elevation, as shown in Figure 4, it presents concave side surfaces. These 10 blades are carefully formed so that the cutter will possess a diameter necessary to produce the concave surfaces 14 on the breast of a heel blank 15 and which concave surfaces 15 extend from the heel seat 16 of the heel to the heel top 17 when said blank is considered from a standpoint of horizontal sections. The concave curvature of the cutter, as viewed in Figure 4, is such as to 20 produce convex surfaces as in 18 on the heel blanks, which surfaces extend vertically from the heel seat to the heel top. When the heel blank is finished the sides 19 thereof are always curved or turned, as indicated 25 in Figures 11 to 14, and it is by virtue of the curved surfaces confining the sides 19 to the compound surfaces of the breast of the heel blank that there is provided on the latter, when it is finished, the straight side edges 20 which have been indicated most clearly in 30 Figure 12. In the present invention it is to be seen that by moving the heel blank 15 outwardly to the cutter, the construction of the latter alone produces the compound curvature in said heel surface and in this manner 35 the machine is independent of the means for holding and advancing the heel blanks into engagement with the cutter. As previously stated, this is a marked contrast with machines heretofore developed for effecting this 40 operation. The essential feature of the present invention therefore consists in the shape of the cutter 9. This cutter is removably mounted on the upper end of the shaft 45 6 to permit convenience in substitution of cutters and to adapt the machine readily to heel blanks of varying sizes and forms.

To advance the heels into engagement with the cutter there has been shown a particular 50 type of table or support, although if desired any ordinary form of table may be used which may be situated near the cutter by means of which blanks may be fed by hand into engagement with the cutter. In the 55 present instance, however, the supporting means comprises an upright 21, which is hinged as at 22 at its lower end in connection with the frame 1. I do not limit myself to a hinged construction since the upright may 60 slide, in fact, the length of the upright 21 is

such that for all practical purposes the heel blank moves in a substantially straight line into and out of engagement with the cutter.

The upper end of the upright 21 carries a 70 table 23, which is pivotally secured to the upper end of the upright as at 24. Both the table 23 and the upright 21 are provided with fixed brackets 25 to which are secured reversely threaded screws 26. These screws are united by a turn buckle 27, by means of 75 which the operative position of the table in relation to the upright may be operated and maintained.

80 Mounted on the upper surface of the table 23 is an angle member 28 and to the vertical leg of this member there is secured as at 29 for vertical adjustments a guide member 30. The front wall of this member, as shown in Figure 7, is provided with a dove tail groove 31, in which is positioned for starting movement the correspondingly formed rib 32 provided upon a vertically movable clamp 33.

85 During the time when the heel blank is presented to the action of the cutter 9, the heel blank is clamped in connection with the table 23 by the clamp 33. This is accomplished by loosely connecting with the upper end of the clamp 33 one end of a lever 34, which is pivoted as at 35 on the guide member 30. The rear end of the lever 34 includes 90 a cam surface 36, with which is engaged the short frame of a bell crank lever 37 which is also pivotally mounted as at 38 on the angle member 28.

95 The outer end of the entire frame of the lever 37 is formed to include a roller 39, which is disposed for engagement with a cam rib 40 provided on the under surface of a stationary frame section 41, the latter being 100 fixed to the stationary upright or standard 8. It will be seen, by reference to Figure 4, that when the heel blank is spaced from the cutter or when the table 23 occupies an inactive or retracted position, the roller 39 will be 105 located in front of the rib 40 but, as shown in Figure 5, when the table is advanced to bring the heel blank into engagement with the cutter, the roller 39 will engage with the forward or under side of the rib 40, so as to 110 rock the lever 34 and thereby force the beveled gripping edge 42 of the clamp 33 into secure holding engagement with the heel blank throughout the entire period when the heel blank is being subjected to the action of the rotary and formed cutter. A spring 43 115 co-operates with the bell crank lever 37 to maintain the roller 39 thereon in constant engagement with the various surfaces of the rib 40.

120 To govern the positions of the heel blank at the forward end of the table and to control the depth of the cut in the heel blank produced by the cutter there is provided, as shown in Figures 9 and 10, an adjustable gauge blade 44. This blade is pivotally 125

mounted as at 45 on the swinging upright 21, and the lower end of the blade includes a roller 46, which is adapted to ride upon an inclined blade 47 carried by the standard 8. 5 When the table is moved away from the cutter and the clamping mechanism elevated the gauge blade responding to the influences of a spring 48 moves upwardly so that the removable gauge strip 49 carried thereby projects slightly above the upper and forward edge of the table 23. This projecting portion of the strip 49 serves as a stop against which the operator of the machine may place the heel blank upon which the breast 10 facing operation is to be performed. Then, as the table advances to present the heel blank to the cutter the roller 46 riding upwardly upon the inclined blade 47, swings said gauge blade so that the strip 49 will be 15 positioned below the upper edge of the table, as shown in Figure 10, and out of the way of the cutter proper. The gauge blade assumes the position shown in Figure 10 during the 20 entire period of engagement between the heel blank and the cutter.

To effect the automatic advance and return movement of the work-supporting table, there is mounted upon the inclined struts 50 of the frame 1 a bed plate 51. Mounted on the bed 25 plate 51 is a motor 52, whose shaft is provided with a pulley. From this pulley there is passed a belt 53 which leads to a speed reducing mechanism 54, also mounted on the bed plate 51. The driving shaft of the 30 mechanism 54 includes a disc 55 to which is eccentrically secured an adjustable strap 56, the latter having its forward end connected with a U shaped yoke 57, which surrounds the shaft 6, and the forward ends of the 35 yoke 57 are pivotally connected with the upright 21 as indicated at 58. It will be seen that by adjustment between the disc 55 and the strap 56, the throw or movement of the table may be regulated to control the 40 depth of the cut produced in the blank. Another adjustment is secured by the turn buckle 27 for the purpose of vertically adjusting the position of the heel blank in 45 relation to the cutter. These combined adjustments adapt practically any type of Cuban heel to the machine. A third adjustment is of course secured by changing the sides of the cutter 9. These cutters are so 50 formed that they can be readily applied to or removed from the upper end of the shaft 6.

gauge strip 49 and that after the breasting operation has been completed, the finished blank may be removed from the table by the operator and another blank placed thereon. The essential feature of the present invention resides in the construction of the cutter which is formed or shaped so that of itself the convex and concave curvature is provided in the heel blank. I prefer to form the blades of the cutter in the helical or spiral manner indicated, for the reason that the blades will thus engage the wooden heel blank more properly or effectively so that the latter is cut or curved as desired without injury, such as splitting or roughly finishing the breast surface of the wooden heel. In this connection it should be observed that the shaft 6 revolves at very high speed and this fact, taken in connection with the shape of the cutter, enables the machine to produce on the breast surface of a heel blank, a sharp curvature or formation as indicated and which surface is characterized by its smooth finish, absence of roughness and other imperfections which have heretofore required an additional sanding or buffing operation.

What is claimed is:

1. In a heel breasting machine, a rotatively mounted cutter, said cutter being formed to comprise a body which carries a plurality of rigidly mounted cutting blades, said blades being disposed in circular order about said body and extending longitudinally and helically with respect to said body, the cutting edges of said blades being curved arcuately so that one end of said cutter possesses greater diameter than the opposite end.
2. In a heel breasting machine, a rotary cutter formed to comprise a body from which rigidly projects a plurality of circularly arranged cutting blades which extend longitudinally and helically of the cutter, said blades being provided with concave cutting edges so that the diameter of the cutter at one end thereof exceeds the diameter of the intermediate portion of said cutter.
3. In a heel breasting machine, a frame, a cutter rotatively mounted in connection with said frame, a work support movable with respect to said frame and cutter, gauge means for determining the operative position of a heel blank on said work support, means for moving said work support toward and from said cutter to present the breast surface of a heel blank carried thereby to

In view of the foregoing it will be seen that by virtue of the construction designated that a simple and improved machine is provided for breasting a heel blank to produce said side edges on such a heel blank where the sides of the blank meet the breasting surface thereof. It will be understood that the heel blanks may be placed by hand on the supporting table in engagement with the said cutter to a predetermined extent, means automatically operable to retain a heel blank in a stationary position on said work support when the heel blank is presented to the cutter, said cutter being so shaped as to produce the convex curve in the breast surface of the heel blank vertically and a concave curve horizontally, and means for rotating said cutter. 125 130

4. In a heel breasting machine, a frame, a cutter mounted for rotation in connection with said frame and revoluble about a stationary vertical axis, a pivotally mounted table movable relatively to said frame and cutter, gauge means arranged at one end of said table for determining the position of a heel blank thereon, means for oscillating said table to present the breast surface of a heel blank carried thereby to said cutter, automatic means for clamping the heel blank to said table when the heel blank is engaged by said cutter, and means for positively moving the gauging means to an inactive position during engagement between the heel blank and cutter.
5. In a heel breasting machine, a rotary cutter formed to comprise a body from which rigidly projects a plurality of circularly arranged cutting blades which extend longitudinally and helically of the cutter, said blades being provided with concave cutting edges so that the diameter of the cutter at each end thereof exceeds the diameter of the intermediate portion of said cutter.
6. In a heel breasting machine, a rotatably mounted cutter, said cutter being formed to comprise a body which carries a plurality of rigidly mounted cutting blades, said blades being disposed in circular order about said body and extending longitudinally and helically with respect to said body, the cutting edges of said blades being so shaped that the intermediate portion of said cutter possesses a diameter less than the ends of said cutter.

In testimony whereof I affix my signature.
FRED A. DAY.
